(57) CLAIM

The ornamental design for a shoe bag, as shown and described.

DESCRIPTION

FIG. 1 is a perspective view of a shoe bag showing my new design;

FIG. 2 is a left-side elevational view thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right-side elevational view thereof;

FIG. 8 is a perspective view of a second embodiment of FIG. 1;

FIG. 9 is a bottom plan view thereof;

FIG. 10 is a front elevational view thereof;

FIG. 11 is a left-side elevational view thereof;

FIG. 12 is a right-side elevational view thereof;

FIG. 13 is rear elevational view thereof; and,

FIG. 14 is a top plan view thereof.

The broken line shown crossing the front and back surfaces of the shoe bag is stitching and forms a part of the claimed design.
